(57) **CLAIM**

The ornamental design for a table lamp base, as shown and described.

DESCRIPTION

FIG. 1 is a front, left, top perspective view of a table lamp base, showing our new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view thereof;

FIG. 9 is an enlarged view of detail 9 in FIG. 2;

FIG. 10 is an enlarged view of detail 10 in FIG. 3;

FIG. 11 is an enlarged view of detail 11 in FIG. 4; and,

FIG. 12 is an enlarged view of detail 12 in FIG. 5.

The dashed broken lines in the figures are for the purposes of illustrating portions of the table lamp base and form no part of the claimed design.

The dash-dot-dash broken line defines the boundary of the enlarged views and form no part of the claimed design.
